UNITED STATES PATENT OFFICE.

SILAS C. SALISBURY, OF NEW YORK, N. Y.

IMPROVEMENT IN GAS-BURNERS.

Specification forming part of Letters Patent No. 177,285, dated May 9, 1876; application filed April 13, 1876.

To all whom it may concern:

Be it known that I, SILAS C. SALISBURY, of New York, in the county of New York and State of New York, have invented a new and useful Improvement in Gas-Burners; and I do hereby declare that the following is a full and exact description of the same, reference being had to the accompanying drawings and to the letters of reference marked thereon.

The object of my invention is the production of a gas-burner, designed more particularly for use in street-lamps and public grounds, which will prevent the blowing of the gas, when the pressure is increased, and regulate the flow so as to deliver the same in a steady stream, thereby insuring the consumption of all the gas, increasing the brilliancy of the light, and making a great saving over burners as heretofore constructed.

My invention therein consists, principally, in the combination, with a gas-burner, of a peculiar valve; and, further, in the combination and construction of the several parts composing my burner, all as more fully hereinafter explained.

To enable others skilled in the art to manufacture my device, I describe the same in connection with the drawings, in which—

Figure 1 is a side elevation of the burner; Fig. 2, a central vertical section of the same; and Fig. 3, a separate view of the lower part of the burner, a part of the valve being broken away to show the course of the gas.

Like letters denote corresponding parts in each figure.

The shell of the burner is constructed in two parts, upper and lower, A A'. The lower part A' has the ordinary open screw-threaded end *a* to be attached to the end of the proper pipe. This lower part is provided with an outwardly-projecting ring, forming a shoulder, *b*, above which the part is screw-threaded, as shown by *b*¹. The inner side of this shoulder forms an expansion-chamber, *b*². The lower end of the upper part A of the burner engages with the screw-thread *b*¹, a small packing-ring, *c*, of paper or other material, being placed on the shoulder *b* to make a gas-tight joint. Above the screw-thread *b*¹ the part A' is contracted at *d*, and closes the hollow interior. One or more holes, *d'*, are made through the top of the contracted end *d*. Over this contracted end *d* loosely rests

a conical-shaped cap-valve, B. This cap is supported and guided in its vertical movement by a wire, *e*, which is secured at its lower end to the top of the contracted end *d*, projects up through the cap B, and has its upper end *e'*, above such cap, bent over to limit its movement. The cap-valve is provided with a number of holes, *f*, in its sides. The upper end of the part A is tipped in any ordinary manner, it being shown as provided with a lava tip, *g*. Below the tip, inside the part A, is placed a wire-gauze diaphragm, *h*, to prevent dust from entering and clogging up the cap-valve. The part A, a short distance above the screw-threaded lower end, and nearly opposite the holes *f* in the valve when in position, is contracted to form on its inner side a shoulder, *i*, lessening the bore of the part A at that point. The valve in its extreme upward movement nearly closes this space.

The operation of my device is as follows: The burner being placed on a street-lamp, for instance, the gas is turned on, and flows freely through the holes *d f*, the wire gauze, and out the burner. When the pressure is increased the valve B is raised, and gradually closes the extent of the space between the valve and the shoulder *i*, thus presenting the gas in a steady stream to the burner, which result is assisted by the expansion-chamber *b*². By these means the blowing of the gas under heavy pressure, and the consequent loss of unconsumed gas, is entirely avoided, and the brilliancy of the light largely increased.

Having thus fully described my burner, and explained some of its advantages, what I claim as new therein, and desire to secure by Letters Patent, is—

The gas-burner described, having in combination the perforated valve B, the wire *e* with its free end serving as a stop, the expansion-chamber *b*², and the wire gauze *h*, substantially as and for the purposes described.

This specification signed and witnessed this 5th day of April, 1876.

SILAS C. SALISBURY.

Witnesses:

WALTER MORRIS,
M. K. SALISBURY.
